UNITED STATES PATENT OFFICE.

ERIC R. LUNDIUS, OF RICHMOND HILL, NEW YORK, ASSIGNOR TO WESTERN ELECTRIC COMPANY, INCORPORATED, OF NEW YORK, N. Y., A CORPORATION OF NEW YORK.

TESTING SYSTEM.

Application filed December 6, 1923. Serial No. 678,933.

To all whom it may concern:

Be it known that I, ERIC R. LUNDIUS, a citizen of the United States of America, residing at Richmond Hill, in the county of Queens and State of New York, have invented certain new and useful Improvements in Testing Systems, of which the following is a full, clear, concise, and exact description.

10 The present invention relates to telephone exchange systems, and more particularly to means for testing portions of the equipment of telephone systems employing automatic switches for the establishment of connections.

15 In machine switching telephone exchange systems calls for unequipped lines are automatically directed to what is called an "intercepted" operator's position. This operator is provided with cord circuits for answering such calls as well as calls intercepted for other reasons. Among the functions required to be performed by such cord circuits are supervision, recall of the operator, 20 call of a distant operator, ringing on retractive calls, extending a call to a subscriber's line, ringing on that line, etc. In order that such cord circuits may function properly at all times, it is necessary to subject their various parts to frequent tests.

25 It is the object of the present invention to provide means which shall be simple, efficient and rapid in operation by which such operator's cord circuits may be tested.

30 A feature of the invention lies in the combination, in a single portable organization, of the circuits necessary to perform all the tests which it is desired to make on such cord circuits.

35 Another feature of the invention lies in the provision of a progressive switch for successively associating the cord circuit with the necessary apparatus to perform the various tests.

40 A further feature of the invention lies in a progressive arrangement of the tests so that they may be made with the greatest efficiency and rapidity.

45 A particular feature of the invention lies in means for associating the cord circuit to be tested with any one of the test circuits of the testing device.

50 These and other features of the invention will be more clearly understood from a 55 consideration of the following description

together with the accompanying drawings and appended claims.

In the drawings, Fig. 1 shows a cord circuit of the type above described; Fig. 2 shows a test set whereby said cord circuit 60 may be submitted to a plurality of tests.

The cord circuit shown in Fig. 1 is of the general type disclosed in the patent of John W. Gooderham, No. 1,504,231 issued Aug. 12, 1924. In addition to the functions above mentioned, this particular cord circuit is also equipped to handle calls where the subscriber calls the operator directly, such as calls for assistance, etc.

The purposes of the various portions of 70 the cord circuit 100 are briefly as follows: plug 101 and its associated apparatus from the answering end of the cord; sleeve relay 102 operates whenever plug 101 is inserted in a jack associated with an incoming line, 75 but marginal sleeve relay 103 operates only in connection with "intercepted" calls. The left winding of supervisory relay 105 has a high resistance while the right winding of that relay has a low resistance. On 80 intercepted calls from a machine switching office, with relay 103 operated relay 105 functions through its high resistance winding. On direct calls relay 105 functions through its low resistance winding and 85 feeds battery to the subscriber's line. On intercepted calls machine ringing is tripped as soon as the listening key 107 is operated, relay 108 initiating the tripping operation. Relays 122 and 123, under the control of the 90 contact of interrupter 124, serve to close the circuit of tripping relay 112, and relay 121, operating in response to the next closure of the contact of interrupter 124, serve to open that circuit. Tripping relay 112 which is 95 slow to release, bridges resistance 126 across the trunk circuit for a period measured by the successive closures of the contact of interrupter 124 and the releasing time of relay 112, which is so adjusted as to permit 100 the tripping of the machine ringing, but not the collection of a coin or the operation of a message register at the machine switching office. In the case of a direct call with relay 110 deenergized, relay 121 is operated im- 105 mediately after the closure of the listening key, preventing the tripping operation. If a subscriber, having talked with the operator, hangs up and immediately thereafter removes his receiver to recall the operator, 110

or merely depresses and releases his switch-hook for that purpose, supervisory lamp 106 is flashed and buzzer 118 sounded through the agency of interrupter 109. Relay 129, which is operated under the control of relay 116, serves to extend the talking conductors to the operator's telephone set 130. Key 114 serves a double purpose, that of flashing the supervisory signal of an operator by means of whom a call may have been extended to this position and, in conjunction with the master ringing key (not shown), to ring back on revertive calls. Keys 145 and 161 serve, respectively, to collect and refund coins which may have been deposited in the extension of a call to this position.

Plug 131 and its associated apparatus constitutes the calling end of the cord circuit 100. The sleeve relay 138 operates on the insertion of plug 131 in an outgoing jack to close the tip conductor of the cord and to light the supervisory lamp 132. Marginal sleeve relay 139 is not ordinarily operated but if the operator should by mistake use the calling end of the cord to answer an intercepted call, it would operate, in turn operating relay 134 to open the ring conductor and prevent an operative connection. Supervisory relay 137 serves to retire lamp 132 when a connection has been established. Key 135 connects dial 150 and relay 149 across the outgoing end of the cord circuit to permit the establishment of connections over the machine switching central office apparatus. Relay 149 is operated when such apparatus is in condition to receive dial pulses and operates relay 152 to extend the "dial tone" to the operator's circuit 130. Key 136 is the ringing key for use on outgoing connections.

The test set shown in Fig. 2 is provided with three jacks by means of which the cord under test may be connected to the testing apparatus. Jack 201 is used for testing the answering end of the cord circuit or answering cord; jack 275 for testing the calling end of the cord circuit or calling cord; and jack 251 in connection with testing the flashing of a distant operator. Switch 200 is a step-by-step switch of the type disclosed in Patent No. 1,472,465, to O. F. Forsberg et al, issued October 30, 1923. It is driven by magnet 207 and in its various positions establishes connections to the jacks 201 and 275 whereby the cord circuit attached thereto may be tested. Brush 203 and the set of terminals engaged thereby complete circuits for lighting the group of progress lamps 218, 221, etc. there being a lamp corresponding to each of the tests which is to be applied. Lamps 202 and 277 mark the positions of the switch from which tests on the answering cord and the calling cord, respectively,

are begun. Where the same tests are made on both answering and calling cord, the same lamp is lighted for both ends of the cord circuit. Lamps 253, 222, 259 and 306 are test lamps. Lamp 222 is lighted as an indication that some lamp in the cord circuit should be lighted. Lamp 253 is lighted in response to action produced in the test set by the cord circuit, while lamps 259 and 306 are lighted at the time that flashing and 70 flashing recall are tested. Brushes 203, 209, 269 and 225 of switch 200 are bridging brushes, that is, make contact with one terminal before leaving the one just preceding. Brushes 234 and 229 are non-bridging, that is, break contact between terminals. Key 205 is used for energizing the stepping magnet of switch 200 and serves to step the switch to a position to associate any desired one of the test circuits with the cord 75 circuit under test. The special function of the keys or switches shown at the lower left corner of the figure will be more clearly understood from the detailed description given hereinafter. Keys 239, 205 and 217 have only one pair of springs and are non-locking. Switches 210 and 211 have two pairs of springs and normally engage one of such pairs. Although for simplicity battery is shown permanently connected to the 80 resistances through which the lamps are lighted, according to the usual custom this battery would be connected to the test circuits by a plug and jack.

A more detailed description of the operation of the circuits will now be given. When a cord circuit such as 100 is to be given a complete test, the answering plug 101 is first inserted in jack 201. If switch 200 is standing with its brushes engaging their normal terminals, lamp 202 will be lighted in a circuit from battery, resistance 204, lamp 202, normal contact and brush 203 to ground. If the switch is standing in any other position, the lamp corresponding to that position will be lighted in a similar circuit. If the switch is standing in any of the positions from 1 to 10, the operation of key 217 will close a circuit from battery through the winding and back contact of stepping magnet 207, brush 269 and the terminal on which it is standing, conductor 276 to ground at the lowermost contact of key 217. Switch 200 will be advanced under the control of this circuit to its No. 11 position which will be indicated by the lighting of lamp 277. Another depression of key 217 will advance the switch to position 12 from which it will be stepped back to normal in a circuit from battery, winding and back contact of magnet 207, conductor 268, brush 269 and its No. 12 to 21 contacts, lower contact of jack 201 to ground.

When switch 200 has reached its normal position as indicated by the lighting of 130

lamp 202, key 205 may be depressed and released. The closure of the key completes a circuit from ground, lower contact of key 205, conductor 206, winding of stepping magnet 207 of switch 200 to battery, in which circuit magnet 207 operates. The release of key 205 permits magnet 207 to retract its armature and advance the brushes of switch 200 onto the No. 1 terminals of their corresponding contact banks. With switch 200 in this position, relay 102 of the cord circuit is automatically given a non-operate test. A circuit may be traced from battery, winding of relay 102, winding of relay 103, sleeve of plug 101, sleeve of jack 201, conductor 208, brush 209, conductor 278, contact 279 of switch 211, resistances 212, 213, 214 and 215, contact 216 of key 217 to ground. Resistances 212-215 are of such value as to produce a current through relay 102 which should just fail to operate it. If the relay is properly adjusted no lamp will be lighted in the cord circuit. Since relay 103 is marginal the current will be still less able to operate that relay. Lamp 218 will be operated to indicate the test which is being made. If relay 102 operates falsely, lamp 106 will be lighted in an obvious circuit and adjustments can be made to bring relay 102 into the proper condition.

Key 205 is again depressed and released to close the above traced circuit of magnet 207 to step the brushes of switch 200 onto their No. 2 terminals. Lamp 221 is lighted in this position of switch 200 indicating an operate test on sleeve relay 102. The circuit of relay 102 is as above traced as far as brush 209 and from thence extends over the No. 2 contact, conductor 288, contact 219 of switch 211, thence through contact 220 of switch 210 in parallel with resistance 227, through resistances 213, 214 and 215, contact 216 of key 217 to ground. The current in this circuit is sufficient to operate relay 102, but still insufficient to operate relay 103, and lamp 106 is lighted. Lamp 222 is also lighted in a circuit from battery through resistance 223, lamp 222, conductor 224, conductor 264, No. 2 terminal and brush 225 to ground. The lighting of lamp 222 is a signal to the operator that a lamp of the cord circuit should be lighted at this time. Switch 210 may now be thrown to its right-hand position, opening the shunt around resistance 227 at contact 220. With resistance 227 in series with resistances 213, 214 and 215 the current through relay 102 is reduced to a point where relay 102 will just remain operated and if that relay is properly adjusted lamp 106 should continue to be lighted. Switch 210 is now restored to its left-hand position.

The next test is applied to supervisory relay 105. Key 205 is depressed and released as before and switch 200 is stepped

on to its No. 3 terminals. Sleeve relay 102 remains operated in this position in a circuit which is the same as previously traced to brush 209 and from thence extends over the No. 3 contact through resistances 213, 214 and 215 to ground at contact 216 of key 217. For this test, listening key 107 is operated. At its middle upper contact key 107 closes a circuit from ground, conductor 170, winding of relay 108 to battery. Relay 108 disconnects interrupter 109 from the front contact of relay 105 and completes a circuit for relay 120 extending from battery, winding of relay 120, left normal contact of relay 121, inner left front contact of relay 108 to ground at the right front contact of relay 102. Relay 120 closes a circuit for relay 121 extending from battery, right winding of relay 121, front contact of relay 120, outer right contact of relay 108, outer left contact of relay 110 to ground at the right front contact of relay 102. Relay 121 operates and locks in a circuit from battery through its left winding, left alternate contact, inner left front contact of relay 108 to ground at the right front contact of relay 102 and in so doing opens the circuit of relay 120. At its right front contact relay 121 closes a circuit for relay 116 extending from battery right winding of relay 116, conductor 127, lowermost contact of key 107, conductor 128 to the right front contact of relay 121. Relay 116 operates. In position No. 3 of switch 200 a circuit for relay 105 is completed from battery through its right-hand low resistance winding, inner right back contact of relay 110, lower left winding of repeating coil 111, lower back contact of relay 112, contact 113 of key 114, ring of plug 101 and jack 201, conductor 228, brush 229 and its No. 3 terminal, conductor 230, resistance 231, through contact 232 of switch 210 in parallel with resistances 237 and 238, No. 3 contact of brush 234, conductor 235, tip of jack 201 and plug 101, contact 115 of key 114, upper back contact of relay 112, left front contact of relay 102, upper left winding of repeating coil 111 to ground at the inner left back contact of relay 110. The current in this circuit is sufficient not only to operate relay 105 but to thoroughly magnetize its core. The operation of relay 105 opens the circuit of lamp 106 and that lamp is extinguished. Although a circuit is completed from ground through the left winding of relay 116, left front contact of relay 116, left front contact of relay 105, through lamp 106 to battery, the resistance of the winding of relay 116 is sufficient to prevent the lighting of the lamp, although relay 116 is locked in the circuit. Switch 210 may now be thrown to its right-hand position removing the shunt around resistances 237 and 238. With these two resistances in the

circuit of relay 105 that relay does not receive sufficient current to remain operated and should release. The release of relay 105 again completes the circuit of lamp 106 and that lamp should light. With switch 210 in its right-hand position, key 239 is depressed, short-circuiting resistances 231 and 238 to produce a current through the supervisory relay sufficient to operate it. The operation of relay 105 should again extinguish lamp 106. Key 239 is now released and switch 210 restored to its left-hand position. During this test, lamp 236 is lighted in a circuit over brush 203. Key 205 is again depressed and released and switch 200 is advanced to its No. 4 position. In this position, marginal relay 103 is tested. In position No. 4 the circuit for supervisory relay 105 is opened at the contact of brush 229. The circuit for relays 102 and 103 extends as previously traced to brush 209 and thence over the No. 4 contact through resistances 214 and 215 and contact 216 of key 217 to ground. The current in this circuit is sufficient to operate relay 102 but is just insufficient to operate relay 103. Lamp 240 is lighted to indicate the test being made and lamp 222 is operated in a circuit from battery resistance 223, lamp 222, conductor 224, contact 241 of switch 211, conductor 281, No. 4 contact and brush 225 to ground, indicating that the lamp of the cord circuit should be lighted. The operation of relay 102 lights lamp 106 and the failure of relay 103 to operate permits its continued illumination. Key 205 is momentarily operated to advance switch 200 to its No. 5 position. In this position the above traced circuit for relays 102 and 103 extends as before to brush 209 and then over its No. 5 terminal (to which are strapped the Nos. 6, 7 and 8 terminals) through resistance 215 to ground at contact 216 of key 217. The current in this circuit is sufficient to operate relay 103 as well as relay 102 and these relays will remain operated throughout positions 5, 6, 7 and 8. Relay 103 closes an obvious circuit for relay 110, which relay operates, opening the circuit through the right-hand low resistance winding of relay 105 and closing a circuit through its left-hand high resistance winding extending from battery through the left winding of relay 105, inner left front contact of relay 110, upper left winding of repeating coil 111, left front contact of relay 102, upper back contact of relay 112, contact 115 of key 114, tip of plug 101 and jack 201, conductor 235, brush 234 and its No. 5 terminal, resistance 242, contact 243 of switch 210 to ground. Supervisory relay 105 operates and opens the circuit of lamp 106. Since relay 116 is operated as previously described, lamp 106 is extinguished. None of the test lamps are

lighted at this time but lamp 244 is lighted to indicate which test is being performed.

Key 205 is now momentarily operated to position the brushes of switch 200 on their No. 6 terminals. Lamp 236 is again operated in this position since the test to be made is also on the supervisory relay. Relays 102 and 103 are operated at this time. If relay 110 has opened its back contacts and closed its front contacts, relay 105 is operated in a circuit from battery through the left winding of relay 105, inner left front contact of relay 110, upper left winding of repeating coil 111, left front contact of relay 102, upper back contact of relay 112, contact 115 of key 114, tip of plug 101 and jack 201, conductor 235, brush 234 and its No. 6 terminal, resistance 242, contact 243 of switch 210 to ground. However, if relay 110 has not opened its back contact, another circuit is available from battery through the right winding of relay 105, inner right contact of relay 110, lower left winding of repeating coil 111, lower back contact of relay 112, contact 113 of key 114, ring of plug 101 and jack 201, conductor 228, brush 229 and its No. 6 terminal, conductor 245, resistance 246 to ground. In either case, lamp 106 will be extinguished. To test in which of these circuits relay 105 is operated, switch 210 is thrown to its right-hand position, opening the circuit through the left-hand high resistance winding of relay 105. If relay 110 has opened its back contact lamp 106 will be lighted since relay 105 will be released. If lamp 106 fails to light, this is an indication that relay 110 is not properly adjusted. At the completion of this test, switch 210 and key 107 are restored, the restoration of key 107 releasing relays 108 and 121. Relay 116 is held operated as long as relay 105 remains operated. Key 205 is now momentarily depressed and switch 200 advanced to its No. 7 position. Lamp 256 is lighted to mark the test to be made, which, in this position, is on the operation of the cord circuit in tripping machine ringing. In position No. 7 both of the previously traced circuits for relay 105 are opened and that relay releases, in turn releasing relay 116. Relays 102 and 103 are maintained energized as described in position No. 5. Another circuit is closed for relay 105 in position No. 7, which may be traced from battery, left winding of relay 105 and thence as previously traced to brush 234, its No. 7 contact, conductor 250, ring contact of jack 251, conductor 252, upper contact of key 205, resistance 246 to ground. Relay 105 reoperates in this circuit. Since listening key 107 is not now closed, a circuit is intermittently completed from battery through lamp 106, front contact of relay 105, left back contact of relay 116, outer left back

contact of relay 108, winding of relay 117 to ground through the contact of interrupter 109. Lamp 106 flashes and buzzer 118 sounds in response to each closure of the contact of interrupter 109. The tester now operates the listening key 107 and closes an obvious circuit for relay 108. The operation of relay 108 closes a circuit for 120 as before. It also transfers the circuit of lamp 106 to ground through the winding of relay 119. Relay 119 operates, but due to its high resistance, lamp 106 is extinguished. Relay 119 closes a circuit from battery, winding of relay 122, left back contact of relay 123, contact of interrupter 124, contact of relay 119, left normal contact of relay 121, inner left contact of relay 108, conductor 104 to ground at the left contact of relay 102. At the first closure of the contact of interrupter 124, relay 122 operates and closes a locking circuit for itself through the winding of relay 123, right front contact of relay 122, left normal contact of relay 121 and thence as above traced to ground. In the succeeding open period of the interrupter, relay 123 operates in this locking circuit and completes a circuit for relay 112 extending from battery, winding of relay 112, outer right front contact of relay 110 conductor 163, normal contact of relay 125, inner right contact of relay 108, right contact of relay 123 to ground at the right back contact of relay 121. Relay 112 operates and bridges resistance 126 across the tip and ring conductors. This closes a circuit for trip relay 249 in the test set, extending from source of ringing current 287, winding of relay 249, left back contact of relay 248, conductor 247, No. 7 contact and brush 229, conductor 228, ring of jack 201 and plug 101, contact 113 of key 114, lower front contact of relay 112, resistance 126, upper front contact of relay 112, contact 115 of key 114, tip of plug 101 and jack 201, conductor 235, brush 234 and its No. 7 contact, conductor 250, ring contact of jack 251, conductor 252, upper contact of key 205, resistance 246 to ground. Relay 249 operates in this circuit, removing the shunt from the operating winding of relay 248 so that this relay operates in a circuit from battery, non-inductive winding of relay 248 operating winding of relay 248, No. 7 contact and brush 203 to ground. The operation of relay 248 lights lamp 253 from ground at the inner right contact of relay 248, lamp 253, resistance 254 to battery. When interrupter 124 again closes its contact, a circuit is completed from battery, through the right winding of relay 121, left front contact of relay 123, contact of interrupter 124, contact of relay 119, left normal contact of relay 121, inner left front contact of relay 108 to grounded conductor 104. Relay 121 operates and locks through its left winding and left alternate contact and the inner left contact of relay 108 to grounded conductor 104. The operation of relay 121 closes a circuit from battery through the right winding of relay 116, conductor 127, lowermost contact of key 107, conductor 128 to ground at the right front contact of relay 121. Relay 116 operates and locks in a circuit from ground through its left winding and left front contact, left front contact of relay 105, lamp 106 to battery. The circuit of relay 119 is opened and that relay releases. The operation of relay 116 also closes a circuit from battery through the winding of relay 129, right middle contact of relay 108, right front contact of relay 116 to grounded conductor 104. The operation of relay 129 closes the tip and ring conductors from the listening key 107 to the operator's telephone circuit 130. The operation of relay 121 also opens the circuit of relay 120 and the locking circuit for relays 122 and 123, permitting these relays to deenergize. The deenergization of relay 123 opens the circuit of relay 112 permitting this relay to deenergize and open the tripping bridge. When relay 112 closes its back contacts a circuit may be traced from source of ringing current 287 through the low capacity condenser 255, left front contact of relay 248, conductor 247, No. 7 terminal and brush 229, thence over the ring conductor, through the repeating coil 111, back over the tip conductor to brush 234 and its No. 7 contact, conductor 250, ring contact of jack 251, conductor 252, upper contact of key 205, resistance 246 to ground. Ringing current induced in this circuit produces a tone in the right windings of repeating coil 111 which is extended through the contacts of key 107 and relay 129, to the operator's telephone circuit 130. When this tone is heard by the tester, he is informed that the tripping feature has functioned properly. The listening key 107 is then restored releasing relays 108, 121 and 129.

Key 205 is again operated and released advancing switch 200 to position No. 8. In this position the flashing recall feature is tested. When brush 234 of switch 200 moves from position No. 7 to position No. 8, the circuit for relay 105 is opened and closed again simulating the action of the subscriber in recalling the operator. Relay 105 releases, opening the locking circuit of relay 116 and then is again operated. The circuit of relay 105 in position No. 8 is the same as previously described except that it extends through contact No. 8 of brush 234 instead of through contact No. 7, contacts Nos. 7 and 8 being strapped together. Relay 105 operates in this circuit and lamp 130

106 flashes in a circuit from battery, lamp 106, left front contact of relay 105, left back contact of relay 116, left back contact of relay 108, winding of relay 117, contact of interrupter 109 to ground. Lamp 259 is lighted at this time over brush 225 to indicate that a flashing lamp should be observed at the cord circuit.

The flashing operation is also tested in this position. To do this the calling plug 131 is inserted in jack 251. The insertion of plug 131 in jack 251 closes a circuit from battery, through the windings of relays 138 and 139, sleeve of plug 131 and jack 251, conductor 261 to ground through the winding of relay 226. Relay 226 operates, disconnecting the source of ringing current 287 and lighting lamp 301 in a circuit from battery resistance 223, lamp 306, inner right contact of relay 226, No. 8 contact and brush 225 to ground to match the cord lamp. Relay 138 also operates and closes a circuit for lamp 132 from battery through that lamp, back contact of relay 137, conductor 140, left front contact of relay 138 to ground, in which circuit lamp 132 lights. The calling cord at this time acts as the calling cord of a distant operator and the supervisory lamp 132 takes the place of the lamp at that operator's position. Flash key 114 is now operated and a circuit is closed from ground, contact 164 of key 114, conductor 162, winding of relay 125 to battery. Relay 125 operates and closes a circuit from ground, front contact of relay 125, conductor 163, outer right contact of relay 110, which is operated since relay 103 is operated, winding of slow-to-release relay 112 to battery. Relay 112 bridges resistance 126 across the tip and ring conductors of the answering cord; but as long as key 114 is held the conductors are open at the contacts of that key, and no circuit is completed. When key 114 is released, relay 125 deenergizes, opening the circuit of relay 112, but since relay 112 is slow-to-release, during the releasing time of that relay a circuit will be completed from battery, lower right winding of repeating coil 111, winding of relay 137 lower normal contacts of keys 136 and 135, contact of relay 134, ring of plug 131 and jack 251, conductor 250, No. 8 contact and brush 234, conductor 235, tip of jack 201 and plug 101, contact 115 of key 114, upper front contact of relay 112, resistance 126, lower front contact of relay 112, contact 113 of key 114, rings of plug 101 and jack 201, conductor 228, brush 229 and its No. 8 contact, conductor 304 tip of jack 251 and plug 131, right front contact of relay 138, upper normal contacts of keys 135 and 136, upper right winding of repeating coil 111 to ground. Supervisory relay 137 operates in this circuit to open the circuit of lamp 132 and extinguish it. As soon as relay 112 re-

leases, this circuit is opened, relay 137 de-energizes and lamp 132 is again lighted. If key 114 is repeatedly depressed, due to the slow-to-release character of relay 112 the bridge 126 will be maintained closed and relay 137 will follow the operation of key 114 to flash lamp 132. Lamp 259 continues to be lighted indicating that a flashing signal is to be expected. At the completion of the test, plug 131 is withdrawn from jack 251, releasing relays 137, 138 and 226, extinguishing lamps 132, 259 and 301.

Key 205 is now operated and released to advance switch 200 to position No. 9. In this position the coin refund and coin collect relays are tested. As soon as switch 200 arrives in position No. 9, lamp 262 is lighted. Lamp 222 is also lighted indicating that a lamp in the cord circuit is to be lighted. Coin return key 161 is now operated to close a circuit from ground through the lower contact of that key and the winding of relay 112 to battery. The operation of relay 112 again bridges resistance 126 across the tip and ring conductors. However, the operation of key 161 also closes a circuit from the source of negative coin return potential, through lamp 141, relay 142, upper contact of key 161 to the upper front contact of relay 112, thence over the tip of the line to brush 234 and its No. 9 terminal, through resistances 263 and 265 to ground. A direct path to ground is also closed over conductor 266 and contact 274 of switch 210 to ground in parallel with resistance 265. Relay 142 operates and lights the coin pilot lamp 143. To test the release of relay 142, switch 210 is thrown into its right-hand position, opening the direct path to ground and introducing resistance 265 in the circuit of relay 142. Relay 142 should release in this circuit extinguishing the coin pilot lamp 143. No current flows over the ring conductor of the cord during this test, since the extension of that conductor is open at the No. 9 terminal of brush 229. Switch 210 and key 140 are then released. Coin collect relay 144 is similarly tested, the circuit in this case extending from positive source of potential through lamp 146, relay 144 and the upper contact of key 145 to the upper front contact of relay 112. The release of the relay is brought about in the same way as for relay 142. Sleeve relay 102 is operated in position 9 over a circuit extending as before to brush 209, and thence over the No. 9 terminal to ground through the winding of relay 226. Relays 102 and 226 are both operated, relay 226, serving to hold source of ringing current 287 disconnected. Relay 103 is not operated, due to the resistance of relay 226. No circuit is completed for relay 105. Lamp 106 is lighted when the coin keys are normal.

Key 205 is again momentarily operated to

advance switch 200 to its No. 10 position. In this position, a ringing test is made which is indicated by the lighting of lamp 302. Key 114 of the cord circuit and the 5 master ringing key (not shown) are operated. A circuit is then completed from the source of ringing current 147, contact 148 of key 114, ring of plug 101 and jack 201, conductor 228, brush 229 and its No. 10 contact, alternating current buzzer 267, No. 10 contact and brush 284, conductor 235, tip of jack 201 and plug 101, contact 133 of key 114 to ground. Buzzer 267 sounds at each closure of key 114. The circuit for sleeve 10 relay 102 is completed as before through the winding of relay 226 to ground.

Having completed the above tests, if for any reason it is desired to repeat the tests on the answering cord, key 217 is depressed, 20 closing a circuit from ground through the lowermost contact of key 217, conductor 276, No. 10 terminal and brush 269, back contact and winding of stepping magnet 207 to battery. The closure of this circuit causes 25 magnet 207 to step switch 200 to its No. 11 position. In this position key 217 is held closed to complete a circuit through the winding and contact of the stepping magnet 207, brush 269 and its No. 11 contact, 30 conductor 270, contact 271 of key 217 to ground, in which circuit switch 200 is stepped to its No. 12 position. A circuit is then immediately closed over conductor 272 to ground at the lower contact of jack 201 35 and, since contacts 12 to 21 of the arc served by brush 269 are strapped together, stepping magnet 207 will be operated to automatically advance switch 200 back to its normal position, whereupon lamp 202 will 40 be lighted and the tests just outlined may be repeated. If it is desired to repeat only one or a few of the tests key 205 may be repeatedly closed to advance the switch 200 to a position to associate the desired test circuit 45 with the cord circuit.

However, if it is now desired to test the calling cord, plug 101 will be withdrawn from jack 201 and plug 131 inserted in jack 275. The insertion of plug 131 into jack 50 275 will automatically advance switch 200 into position 11 by means of a circuit extending from battery through the winding and back contact of stepping magnet 207, brush 269 and its No. 10 terminal, conductor 276, lower contact of jack 275 to ground, which circuit is interrupted as soon as the 55 switch reaches its No. 11 position. In position No. 11, lamp 277 is lighted to indicate that the apparatus is ready to make tests on the calling cord.

Key 205 is now operated and switch 200 stepped to its No. 12 position. Since the plug has been removed from jack 201 the circuit previously traced for advancing the 60 switch back to normal is open at this time.

In position No. 12 a non-operate test is made on sleeve relay 138. The circuit is completed from battery through the winding of relays 138 and 139, sleeve of plug 131 and jack 275, conductor 208, brush 209 and its 70 No. 12 terminal, conductor 278, contact 279 of switch 211, resistances 212, 213, 214 and 215 to ground at contact 216 of key 217. Resistances 212-215 reduce the current in this circuit so as to just not operate relay 75 138. Lamp 218 is lighted as in the case of the non-operate test on the sleeve relay of the answering cord. None of the test lamps are lighted and if relay 138 is properly adjusted, lamp 132 is not lighted. 80

Key 205 is now again operated and switch 200 advanced to its No. 13 position. In this position an operate test is made on the sleeve relay indicated by the lighting of lamp 221. Lamp 222 is lighted over conductors 224 and 264 and No. 13 contact of brush 225 to ground. The circuit for relay 138 extends from the sleeve of jack 275, conductor 208, brush 209 and its No. 13 contact, conductor 288, contact 219 of switch 90 211, contact 220 of switch 210 in parallel with resistance 227, and then through resistances 213, 214 and 215 to ground at contact 216 of key 217. With resistances 213, 214 and 215 in the circuit, relay 138 should 95 operate and lamp 132 should be lighted. Switch 210 may now be thrown to its right-hand position, opening contact 220 and introducing resistance 227 in the circuit of relay 138. This resistance reduces the current to the lowest value which should hold relay 138 operated, and if that relay is correctly adjusted, lamp 132 remains lighted. Relay 139 is marginal and the currents at 100 this time are not sufficient to operate it. 105

Key 205 is now operated to advance the switch 200 to its No. 14 position. In this position a circuit may be traced from battery, lower right winding of repeating coil 111, winding of supervisory relay 137, lower 110 normal contacts of keys 136 and 135, contact of relay 134, ring of plug 131 and jack 275, conductor 228, brush 229 and its No. 14 terminal, conductor 230, resistance 231, contact 232 of switch 210 in parallel with resistances 237 and 238, No. 14 terminal and brush 284, conductor 235, tip of jack 275 and plug 131 right front contact of relay 138, upper normal contacts of keys 135 and 136, upper right winding of repeating coil 111 115 to ground. Relay 138 is maintained energized in position No. 14 in a circuit which is the same as that previously traced as far as brush 209 and then extends over the No. 14 contact, through resistances 213, 214 and 215 to ground at contact 216 of key 217. The continued energization of relay 138 holds lamp 132 lighted. Lamp 236 is lighted 120 to indicate that the supervisory relay is under test. The circuit above traced for 125 130

relay 137 through resistance 231 provides ample current to operate relay 137 and magnetize its core. Lamp 132 is extinguished on the operation of relay 137 since its circuit is opened at the contact of that relay. Switch 210 may now be moved to its right-hand position, removing the shunt from resistances 237 and 238, thus reducing the current to a point where relay 137 releases 10 and lamp 132 is again lighted. With switch 210 in its right-hand position, key 239 is operated shunting resistances 231 and 238, increasing the current to the value which should operate relay 137. If that relay operates, lamp 132 is again extinguished. At the completion of these tests, switch 210 and key 239 are restored.

Key 205 is now operated to advance switch 200 to position No. 15 in which a non-operate test is made on the marginal relay 139 as indicated by the lighting of lamp 240. The circuit of relay 139 is extended as before traced to brush 209, and thence through the No. 15 contact, resistances 214 and 215 to ground at contact 216 of key 217. The current in this circuit is not sufficient to operate relay 139 though relay 138 is operated. Supervisory relay 137 is maintained energized in position 15 20 in a circuit which extends as before to the ring of plug 131 and jack 275 and from thence to brush 229 and its No. 15 contact, through resistances 280 and 231, contact 232 of switch 210, conductor 233, No. 15 contact 30 and brush 234, conductor 235, tip of jack 275 and plug 131 and from thence as before traced to ground. With relay 137 operated and relay 139 not operated, lamp 132 is extinguished. None of the test lamps are lighted at this time.

Key 205 is now operated to advance switch 200 to position No. 16. Lamp 244 is lighted to indicate that an operate test is to be made on a marginal sleeve relay. 45 The circuit of relay 139 extends as before to brush 209 and from thence over its No. 16 contact, through resistance 215 to ground at contact 216 of key 217. Relay 137 is held operated in the circuit traced in position 15, since terminals 15 and 16 in the banks associated with brushes 234 and 229 are strapped together. The current in the above traced 50 circuit for relay 139 is sufficient to operate that relay and its operation closes a circuit for relay 134 which in turn opens the circuit of relay 137. With the deenergization of relay 137, lamp 132 is caused to light. Lamp 222 is lighted at this time to indicate that the supervisory lamp should be lighted.

60 Key 205 is now depressed and released to advance switch 200 to its No. 17 terminals. In this position relay 149 is tested, lamp 303 being lighted to mark this test. Relay 138 is held operated, the circuit extending 65 as before to brush 209 and thence over the

No. 17 contact through resistances 213, 214 and 215, contact 216 of key 217 to ground. The inclusion of resistances 213 and 214 in this circuit prevents the operation of relay 139. Key 135 of the cord circuit is operated connecting relay 149 and the dial 150 across the outgoing ends of the tip and ring conductors. The circuit of supervisory relay 137 is opened and that relay deenergizes. Therefore, with relays 139 and 137 deenergized, lamp 132 should be lighted. A circuit is completed from ground on the No. 17 contact associated with brush 234, brush 234, conductor 235, tip of jack 275 and plug 131, right front contact of relay 138, upper alternate contact of key 135, conductor 155, through the winding of relay 149, contact 151 of dial 150, conductor 154, lower alternate contact of key 135, back contact of relay 134, ring of plug 131 and jack 275, conductor 228, brush 229 and its No. 17 contact, conductors 284, and 285, outer left back contact of relay 226, contact 286 of switch 210 in parallel with resistance 282, through resistance 283 to battery. Relay 149 should operate in this circuit closing a circuit from ground at its contact, left back contact of relay 129, winding of relay 152 to battery. Relay 152 operates to extend the tip and ring conductors to the operator's telephone circuit 130. A tone will be produced in the receiver 153, transmitted thereto over a circuit extending from source of ringing current 287, outer right back contact of relay 226, through low capacity condenser 255, conductor 284, No. 17 contact and brush 229, conductor 228, ring of jack 275 and plug 133, back contact of relay 134, lower alternate contact of key 135, conductor 154, through the condenser 156, left front contact of relay 152, conductor 158, thence through the telephone circuit 130, back to conductor 157, right front contact of relay 152, contact 159 of dial 150, conductor 155, upper alternate contact of key 135, right front contact of relay 138, tip of plug 131 and jack 275, conductor 235, brush 234 and its No. 17 contact to ground. This tone will indicate that relay 149 has operated properly. Switch 210 is now moved to its right-hand position, removing the shunt from resistance 282. With the addition of resistance 282 to the circuit of relay 149 that relay should release, opening the circuit of relay 129 and removing the tone from the telephone set 130. Switch 210 and key 135 may now be restored.

Position No. 18 of switch 200 is not, in the present disclosure, equipped with any test circuit. Hence key 205 must now be depressed and released twice advancing switch 200 to position 19 in which position ringing test is made. In this position the circuit for relay 138 extends from brush 209 over the No. 19 contact to ground.

- through the winding of relay 226. Relays 138 and 226 are operated, relay 226 disconnecting source of ringing current 287. The operation of relay 138 causes the lighting 5 of the lamp 132. Lamp 302 is lighted to indicate that ringing test is being made. Ringing key 136 is operated and a circuit completed from source of ringing current 160, lower alternate contact of key 136, lower 10 normal contact of key 135, back contact of relay 134, ring of plug 131 and jack 275, conductor 228, brush 229 and its No. 19 terminal, through alternating current buzzer 267, No. 19 terminal and brush 234, conductor 235, tip of jack 275 and plug 131, front contact of relay 138, upper normal contact of key 135, upper alternate contact of key 136 to ground. Buzzer 267 sounds in response to each operation of key 136.
- 15 Having ascertained that ringing takes place properly, key 217 is operated, advancing switch 200 through its Nos. 20 and 21 positions back to normal, in a circuit from battery, winding and back contact of magnet 207, brush 269 and its Nos. 20 and 21 contacts, which are strapped together, conductor 272, contact 273 of key 217 to ground. As soon as switch 200 reaches normal position, the previous circuit for lamp 202 is 20 closed indicating that the apparatus is ready to test another cord circuit or to repeat the tests of this circuit.
- If cord circuit 100 is used in connection with directly dialed calls, marginal relay 103 is not operated. Also there is no machine ringing to be tripped. Hence a cord circuit intended solely for this type of traffic would lack relays 103 and 110 and the tripping apparatus. In consequence, in testing such a cord circuit, the tests on the marginal relay and the tripping apparatus would be omitted. The test set shown in Fig. 2 may be adapted for testing such a cord circuit by moving switch 211 into its right-hand position. With the switch in this position, the circuit of the sleeve relay extends from sleeve of jack 201, conductor 208, brush 209 and from thence; over the No. 1 contact, by way of conductor 278, contact 281 of switch 211, conductor 292, resistances 289 and 290 in series, contact 216 of key 217 to ground; and over the No. 2 contact by way of conductor 288, contact 293 of switch 211, conductor 294, through resistance 290 alone, to ground at contact 216 of key 217. In position 3 the circuits are the same as previously traced for the test of the supervisory relay. When switch 200 is stepped into position No. 4 a circuit is closed from battery through the winding and back contact of stepping magnet 207, conductor 295, contacts 296 and 298 of switch 211, conductor 281, No. 4 contact and brush 225 to ground. Switch 200 is stepped to position No. 5 in which position a circuit is completed from
- battery through the winding and back contact of magnet 207, conductor 295, contacts 296, 298 and 300 of switch 211, conductor 299, the Nos. 5, 6 and 7 terminals and brush 225 to ground. Switch 200 is stepped through positions Nos. 5, 6 and 7 to position No. 8 where the flashing recall test is made as previously described. The remaining tests are made in subsequent positions as above described. The switch also passes through the positions for testing the marginal relay of the calling cord. The momentary operation of key 205 advances the switch from position 14 to position 15. With switch 211 in its right-hand position, a circuit is completed for stepping magnet 207 from battery, winding and back contact of the magnet, conductor 295, contacts 296, 298, 300 and 306 of switch 211, conductor 307, No. 15 contact and brush 225 to ground, in which circuit switch 200 is stepped to position 16. In position 16 a circuit is closed from battery, winding and back contact of magnet 207, conductor 295, contacts 296 and 298 of switch 211, conductor 281, No. 16 terminal and brush 226 to ground, for stepping switch 200 into its No. 17 position. No circuit is completed for magnet 207 in position No. 17 and switch 200 comes to rest in position to test relay 149 of the cord circuit. Ringing test is made in position 19 as in the case of cord 100.
- The following is a tabulation of the tests, positions of switch 200 and signals displayed for correct functioning of the cord circuit:
Positions of switch 200	Tests	Signal of cord circuit	Testlamp lighted	Progress lamp lighted
Normal (answering cord)				105
1	Relay 102 (non-operate).			202
2	Relay 102 (operate).	106	222	218
3	Relay 105 (low resistance winding).			221
4	Relay 103 (non-operate).	106	222	236 110
5	Relay 103 (operate)			240
6	Relay 105 (high resistance winding).			244
7	Tripping.	106 (flash) (Tone).	253	256 115
8	Flash and flashing recall.	106 (flash) 1132 (flash)	259 and 306	257
9	Coin return and coin collect.	1143 and 1411	222	262
10	Repetitive ringing.	1143 and 146 (Buzzer 267).	302	303
11 (calling cord)				277 120
12	138 (non-operate).			218
13	138 (operate).	132	222	221
14	137.			236
15	139 (non-operate).			240
16	139 (operate).	132	222	244
17	149.	132		303
18	Ringing.			302 125
19		132 (Buzzer 267).		

From the foregoing description and table, it will be readily seen that a complete test of the cord circuit may be made with this 133

arrangement in a very brief time. Should it become necessary to adjust any of the apparatus, the lamp indicating the point at which the tests have been stopped will remain lighted until the adjustment is completed, after which, the subsequent tests may be made. From the table it is evident that whenever a cord circuit signal should be operated to indicate the correct operation 10 of the cord circuit, lamp 222 in the test set is displayed, and that special lamps indicate special tests. The lighting of lamp 132 in positions Nos. 17 and 19 is merely incidental to the tests being performed.

15 The values of the resistances included in the various circuits will be determined from the actual conditions which must be met by the cord circuit in practical operation.

What is claimed is:

20 1. In a telephone exchange system, a cord circuit, at test set comprising a plurality of test circuits, a progressively operable switch for successively associating said cord circuit with said test circuits, and means 25 for operating said switch to associate said cord circuit with any one of said test circuits.

2. In a telephone exchange system, a cord circuit, a test set comprising a plurality of 30 test circuits, a progressively operable switch for successively associating said cord circuit with said test circuits, means for operating said switch to associate said cord circuit with any one of said test circuits, 35 and means to indicate that said cord circuit and said test circuit have been so associated.

3. In a telephone exchange system, a cord circuit, a test set comprising a plurality of test circuits, a multi-position switch for associating said cord circuit with said test circuits and means for advancing said switch to a particular position to associate said cord circuit with a particular test circuit.

4. In a telephone exchange system, a cord circuit, a test set comprising a plurality of test circuits, a multi-position switch for associating said cord circuit with said test circuits, means for advancing said switch to a particular position to associate said cord circuit with a particular test circuit, and means to indicate when said switch has arrived in such position.

5. In a telephone exchange system, a cord circuit, a testing device for testing said cord circuit comprising a plurality of test circuits, an automatic switch, manual means for advancing said switch to successively associate said test circuits with a cord circuit,

and means to indicate which of said test circuits is effective.

6. In a telephone exchange system, a cord circuit having an answering end and a calling end, a test set comprising a multi-position switch, a plurality of test circuits adapted to be associated with the answering end of the cord circuit in one group of positions of said switch and a plurality of test circuits adapted to be associated with the calling end of the cord circuit in another group of positions of said switch, means for starting the operation of said switch and means for indicating when said switch arrives in the first position of each group of positions.

7. In a telephone exchange system, a cord circuit having an answering end and a calling end, a test set comprising a multi-position switch, a plurality of test circuits adapted to be associated with the answering end of the cord circuit in one group of positions of said switch, and a plurality of test circuits adapted to be associated with the calling end of the cord circuit in another group of positions of said switch, means for initiating the operation of said switch, and means actuated in response to the connection of one end of said cord circuit with said test set and the operation of said initiating means to automatically position said switch in the first of the group of positions corresponding to the end of the cord so connected.

8. In a telephone exchange system, a cord circuit having an answering end and a calling end, a test set comprising a multi-position switch, a plurality of test circuits adapted to be associated with the answering end of the cord circuit in one group of positions of said switch, and a plurality of test circuits adapted to be associated with the calling end of the cord circuit in another group of positions of said switch, means for initiating the operation of said switch, means actuated in response to the connection of one end of said cord circuit with said test set and the operation of said initiating means to automatically position said switch in the first of the group of positions corresponding to the end of the cord so connected, and means to indicate the arrival of said switch in such position.

In witness whereof, I hereunto subscribe my name this 30th day of November A. D. 1923.

ERIC R. LUNDIUS.
